UNITED STATES PATENT OFFICE.

JAMES R. WERTH, OF RICHMOND, VIRGINIA.

JAR-CLOSURE.

1,163,576.

Specification of Letters Patent. Patented Dec. 7, 1915.

Application filed January 26, 1915. Serial No. 4,462.

To all whom it may concern:

Be it known that I, JAMES R. WERTH, a citizen of the United States, residing at Richmond, in the county of Henrico and State of Virginia, have invented certain new and useful Improvements in Jar-Closures, of which the following is a specification.

This invention relates to closures for preserving jars and has for its object to provide a construction of jar and cap which will insure an effective so-called "top closure" and is distinguished by its simplicity and strength of construction.

Another object of the invention resides in providing a clamp or clasp which imparts different degrees of pressure on the cap, that is, a tight grip and a semi-tight grip, the latter being used while the contents of the jar are being treated in the boiler or vacuum chamber.

Still another object of the present invention is to provide a reversible jar, that is the jar is stood on the cap during storage.

It has been found that some preserves improve by inverting the jar and that the contents themselves provide an additional seal for the jar. It is also found to be of great advantage to stand the jar on the cap while the contents are cooled, and by the provision of the feet on the cap the jar is raised from the table while being cooled, so that air can pass all around it not only around the sides and bottom, but also under the cap which imparts a more even cooling. The contraction will therefore be perfectly even on all parts of the jar and its closure.

It will be evident from the drawing that the clamp, when on tight, only engages under the shoulder of the head and on the flat center portion of the cap, while standing free in all other places. The advantage of this is that the cap will get a central pressure which will distribute evenly all around the edge of the cap and on the packing ring therefor. Lastly I provide a sealing for the clamp consisting in a wire drawn around the lower end of the clamp and the clamping lever and this wire might have a lead seal. The unbroken seal will then show the customer that the contents of the jar have not been tampered with.

In the accompanying drawing one embodiment of the present invention is illustrated in which—

Figure 1 shows a vertical axial section of the jar with the cap clamped down tight

and sealed; Fig. 2 is a similar view to Fig. 1 showing the clamp in a "semi-tight grip;" Fig. 3 is a perspective view of the clamp alone; Fig. 4 is a top plan view of the cap; Fig. 5 is a section along line 5—5 of Fig. 4; Fig. 6 is a side view of the cap seen from the left side of Fig. 4; Fig. 7 is a view similar to Fig. 2 with the clamp loosened, that is, with the lever pointing upward; and Fig. 8 is an elevation of the jar and closure assembled and placed in inverted position.

In Figs. 1 and 2, 10 indicates the jar and 11 its flat head provided with a square shoulder at 12 where it joins the neck 13 on the jar. An annular groove 9 is provided in the upper flat surface of the head. The cap 14, as best shown in Fig. 5, is cylindrical with its top portion made in the shape of a conic frustum providing a small central portion 15 which is flat. The top has two segmental reinforcements 16 which are level with the central portion 15 and provided with four feet or projections 17. As seen from the top, the cap will then give the appearance of being divided into four approximately equal quarters, of which two are conical namely, the ones marked 18, and two flat ones 16 which run straight into the central portion 15. Diametrically opposite and near the edge of the cap are provided two studs 19 on the conical surfaces of the cap. These studs are not so high as the flat portions 16, but high enough to engage with the clamp when in position as will be more fully explained later on. The projections or feet 17, however, are higher than the greatest thickness of the clamp so that when the jar is sealed with the clamping position, the jar will be raised above the floor or the table on which it stands when it is inverted so that neither the cap itself, nor the clamp will come into contact with the foundation, thus providing a perfect air circulation all around the jar, not only on the top and sides, but also underneath it.

On its under side the cap is provided with a cylindrical reinforcement of approximately the same diameter as the opening of the neck which it is intended to enter when in position. The edge of the cap forms a square collar or flange around this cylindrical portion 20 of the cap, and is intended to receive a washer 21 of suitable packing material, and this washer is of a corresponding width to the flat top of the head. It will be observed that no annular ridges are pro-

vided either on the cap or on the head, but that the adjacent surfaces are perfectly smooth with the exception of the opposing grooves 9 and 40 of the head and flange respectively, so that a knife or thin blade may be inserted between the cap and the jar to facilitate the opening.

The clamp consists of a flat band with a rectangular middle portion 22 having depending arms 23, 24 at right angles to the middle portion 22. At the bend of the arm, the strap or clamp is provided with two slots 25 of approximately the same width as the studs 19 on the top of the cap. When the clamp is placed in position, these slots will be engaged by the studs which insure the correct positioning of the clamp over the cap. One of the depending arms 23 has a downward extension 26, the free end 27 of which is bent outward to form a shelf or support for the sealing wire 28, and the opposite arm 24 is similarly provided with a shelf 29 for the same purpose. The arm 23 has a square shoulder or offset 30 where it is joined by the extension 26, and this shoulder 30 is intended to grip under the head at 12.

In the arm 24 is provided a slot 31 in which a lever 32 is journaled at 33. This lever has an inwardly extending head 34, and this head is constructed with its greatest eccentricity 35 approximately in the direction of the free arm of the lever as best seen in Fig. 1 where this portion of the head engages with the square shoulder 12 of the jar. And the lever head 34 has moreover a smaller eccentric 36 approximately at right angles to the arm as best shown in Fig. 2 where the lesser eccentric engages with the square shoulder of the jar. Between the two eccentrics 35 and 36 is provided a sharp corner 37 which forms a stop against the neck of the jar when the lever 32 is in its middle position, that is, when it gives its "semi-tight grip". In Fig. 7 the lever is shown pointing upward and the eccentric head completely disengaged from the square shoulder 12 and the clamp ready to be removed. The middle portion 22 of the clamp is so constructed that it imparts pressure to the eccentric head even when engaged as shown in Fig. 2. In consulting this figure it will be evident that the right hand end of the middle portion 22 is raised higher up from the cap than is the case with the left hand end, thereof, but that in Fig. 1 both ends are equally depressed toward the cap but still leaving a free space between the edge of the cap and the clamp, and over the conical surfaces so that a central downward pressure will be imparted by the clamp to the cap, while at the same time the clamp is engaged by the two small studs 19. It will also be evident from Fig. 1 that with the jar inverted a space will be left between the

foundation it stands on and the clamp, permitting air to pass under the cap in this position. Beside the sealing band 28, I also provide a second band or wire 38 which engages the notch 39 near the extreme end of the lever 32, and at the joined ends of this wire, I may place a seal 41 to prevent tampering with the clamp and insuring that the contents of the jar are intact when reaching the consumer.

It will be obvious that the construction of the cap in this case makes it extremely strong and practically unbreakable both during the treatment or the preserving, as well as during transportation. The cap has a reinforcement 20 on its underside, as well as a reinforcement 16 on the upper side, not to mention its great depth at the center caused by the conical shape of the cap.

I claim:—

1. A jar closure comprising a cap with a top in the shape of a conic frustum, the head of the jar having an annular recess, a clamp engaging with the flat portion of the frustum and with the recess on two opposite sides of said head, and means on the clamp for making a tight grip and a semi-tight grip in said recess.

2. A jar closure comprising a cap with a top in the shape of a conic frustum, the head of the jar having a square shouldered neck, a clamp engaging with the flat portion of the frustum and with the shoulder on two opposite sides of said neck, and means on the clamp for making a tight grip and a semi-tight grip, said means comprising a member having an eccentric head engaging under said shoulder and constructed to have two engaging positions corresponding to said two grips.

3. A jar closure comprising a cap with a top in the shape of a conic frustum, the head of the jar having a square shouldered neck, a clamp engaging with the flat portion of the frustum and with the shoulder on two opposite sides of said neck, a lever having an eccentric head hinged on said clamp and engaging under the square shoulder, said clamp being open when the lever is turned upward, but making a tight grip when the lever points downward and a semi-tight grip when it points straight out.

4. A jar closure comprising a cap with a top in the shape of a conic frustum, the head of the jar having a square shouldered neck, a clamp in the shape of a rectangularly bent strap having a middle flat portion for engaging the top of the frustum and depending arms at each end for engaging said shoulder, and means including a cam faced lever on one of said arms, said lever having two different locking positions for imparting different degrees of pressure on the center of the cap.

5. A jar closure comprising a cap with a

top in the shape of a conic frustum, the head of the jar having a square shouldered neck, a clamp in the shape of a rectangularly bent strap having a middle flat portion for engaging the top of the frustum and depending arms at each end for engaging said shoulder, and means on one of said arms including a bent lever for imparting different degrees of pressure on the center of the cap, and sealing means for securing the clamp when imparting its greatest amount of pressure, said sealing means comprising recessed extensions on said arms and said lever, and a tightly drawn band wound around the jar and over said recesses.

6. A jar closure comprising a cap with a top in the shape of a conic frustum, the head of the jar having a square shouldered neck, a clamp in the shape of a rectangularly bent strap having a middle flat portion for engaging the top of the frustum and depending arms at each end for engaging said shoulder, lateral positioning means including studs on the cap and apertures at the bends of said cap for preventing side-slipping of said strap.

7. A jar closure comprising a cap with a top in the shape of a conic frustum, the head of the jar having a square shouldered neck, a clamp in the shape of a rectangularly bent strap having a middle flat portion for engaging the top of the frustum and depending arms at each end for engaging said shoulder, a pair of studs situated diametrically opposite near the edge of the conical surface of said cap, said strap having corresponding holes in the middle flat portion and the depending arms for positioning the clamp over the cap.

8. A jar closure comprising a cap having a flat top face, and beveled recesses diametrically opposite in the top face terminating with a flat central portion, the head of the jar having a square-shouldered neck, a clamp engaging with said flat central portion and said clamp being provided with depending arms for engaging with the shoulder on two opposite sides of the neck while standing free over said recesses, projections on said recesses and corresponding apertures at the juncture of said arms with the main portion of the clamp for positioning the clamp.

9. A jar closure comprising a cap having a flat top face, and beveled recesses diametrically opposite in the top face terminating with a flat central portion, the head of the jar having a square-shouldered neck, a clamp engaging with said flat central portion and said clamp being provided with depending arms for engaging with the shoulder on two opposite sides of the neck while standing free over said recesses, a plurality of upward projections in the shape of studs on said top face, said projections extending beyond the upper surface of the clamp to form feet for the jar when reversed, whereby a space will be formed beneath the jar when so positioned for the free passage of air in all directions under the inverted jar.

The foregoing specification signed at Richmond, Va., this 5th day of January, 1915.
